STORAGE RACK FOR SUSPENDING CONTAINER LIDS

Philip Grasso, P.O. Box 8107, Stanford, Calif.

Filed Jan. 23, 1962, Ser. No. 68,478

Term of patent 14 years

(Cl. D33—3)

FIG. 1

FIG. 4

FIG. 2

The broken line portion of FIGURE 1 is for illustrative purposes only.

I claim:

The ornamental design for a storage rack for suspending container lids, as shown and described.
